WALLBOARD JOINT FINISHING TOOL

Frank Dybdahl, R.F.D., Scottsbluff, Nebr.

Filed Aug. 18, 1958, Ser. No. 755,592

1 Claim. (Cl. 15—235.8)

This invention relates to new and useful improvements in wallboard joint finishing tools and has for its primary object to provide, in a manner as hereinafter set forth, novel means whereby a smooth, uniform crowned joint with feathered edges may be expeditiously produced with unskilled or semi-skilled labor.

Another important object of the present invention is to provide a wallboard joint finishing tool of the character described comprising a scraping blade and a smoothing blade or shoe, wherein said smoothing blade or shoe may be readily adjusted as desired.

Other objects of the invention are to provide a wallboard joint finishing tool of the aforementioned character which will be comparatively simple in construction, strong, durable, compact, of light weight and which may be manufactured at low cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in front elevation of a finishing tool constructed in accordance with the present invention, showing the device in use;

Figure 2 is a view in horizontal section through the wall structure, showing the tool in bottom plan; and

Figure 3 is a sectional view, taken substantially on the line 3—3 of Figure 2.

Referring now to the drawing in detail, it will be seen that the embodiment of the invention which has been illustrated comprises a scraping blade 4 of suitable metal, which blade may also be of any desired dimensions. The blade 4 terminates in angularly bent, downwardly divergent end portions 5 providing handles having secured on one of the longitudinal edges thereof grips 6 of substantially U-shaped cross-section. Between the end portions 5 thereof, the blade 4 is provided with a concave scraping edge 7.

Mounted on top of the scraping blade 4 is a smoothing blade or shoe 8, also of suitable metal. The smoothing blade or shoe 8 is arcuate and the curvature thereof

2

conforms to that of the scraping edge 7 of the blade 4. The smoothing blade or shoe 8 is mounted on the scraping blade 4 at right angles thereto and is secured thereon by means comprising a flange 9 and countersunk bolts 10.

5 The flange 9 is integral with the smoothing blade or shoe 8 and extends at right angles therefrom. Slots 11 in the flange 9 receive the bolts 10 and permit adjustment of the blade 8 on the blade 4.

It is thought that the use of the tool will be readily apparent from a consideration of the foregoing. Briefly, the mud or mastic 12 is applied to the work, as indicated at 13, in the usual manner. The blade 4 is then engaged transversely with the work in a manner to bridge the joint, the operator holding the grips 6 in the hands.

15 The device is then drawn over the work substantially in the manner of a drawknife, the concave scraping edge 7 of the blade 4 uniformly distributing the mastic in addition to crowning and feathering the joint. Excess mastic accumulates on the blade 4. The arcuate trailing

20 blade 8 smoothes the joint. The angularly extending end portions 5 of the blade 4 ride on the work on opposite sides of the joint and stabilize said blade, preventing the same from rocking, etc. By loosening the nuts 14 on the bolts 10, the smoothing blade or shoe 8 may be adjusted as desired relative to the scraping edge 7.

25 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to falling within the scope of the invention as claimed.

What is claimed as new is as follows:

30 35 A wallboard joint finishing tool comprising: a blade engageable transversely with the joint and including a concave arcuate, bottom scraping edge, said blade further including angularly extending, forwardly divergent end portions providing operating handles and operable on the wall on opposite sides of the joint for stabilizing said blade, an arcuate smoothing shoe for the joint mounted on the rear of the blade in laterally extending position and having a bottom face curved permanently in conformity with said edge of said blade, said smoothing shoe including a mounting flange engaged with the blade, said flange having slots therein, and securing elements on the blade engaged in the slots for adjustably fastening the shoe on said blade.
